UNITED STATES PATENT OFFICE.

MABEL LEORA EVENS AND PAUL H. LINDNER, OF CHICAGO, ILLINOIS.

DESIGN FOR A BUTTON.

No. 38,032.

Specification for Design.

Patented May 29, 1906.

Application filed March 19, 1906. Serial No. 308,934. Term of patent 14 years.

To all whom it may concern:

Be it known that we, MABEL LEORA EVENS and PAUL H. LINDNER, citizens of the United States, residing at Chicago, in the county of Cook and State of Illinois, have invented a new, original, and ornamental Design for Buttons, of which the following is a specification, reference being had to the accompanying drawing, forming part thereof.

The figure is a face view of a button, showing our new design.

We claim—
The ornamental design for button, as shown.

MABEL LEORA EVENS.
PAUL H. LINDNER.
